STARTING MECHANISM FOR FLUORESCENT LAMPS

Adolf G. Mueller, Stratford, Conn., assignor to
General Electric Company, a corporation of
New York

Application April 25, 1940, Serial No. 331,566

3 Claims. (Cl. 200—142)

This invention relates to starting mechanisms for electric discharge devices, and more particularly to a starting mechanism for a fluorescent lamp of the well-known commercial type now in use.

An object of the invention is to provide an improved starting switch formed with a housing and connecting means such that it may be readily connected and disconnected from the lamp operating mechanism.

In the accompanying drawing Fig. 1 is a view of a fluorescent lamp and associated starting mechanism constructed in accordance with this invention; Fig. 2 is an elevational view of the starting mechanism and supporting socket therefor; Fig. 3 is a view of the supporting socket taken along the line 3—3 of Fig. 2; Fig. 4 is an exploded view showing the details of the starting mechanism; Fig. 5 is a diagrammatic view showing the manner in which the starting mechanism and fluorescent lamp are connected in circuit, and Fig. 6 is a perspective view of the supporting socket for the starting mechanism.

Referring to the drawing, Fig. 1 illustrates an electric discharge device such as a fluorescent lamp 10 supported at each end on sockets 11, the sockets themselves being mounted on a supporting strip or reflector base 12 of a lamp fixture, or the like. This is one of the ways employed in mounting a fluorescent lamp in fixtures or reflectors for use in a wide variety of installations. Fluorescent lamps of the type mentioned require a starting switch for applying current to the cathodes of the lamp to heat them to a point at which they become emissive, and an impedance, such as a reactor, to limit the current flow through the cathode. Once the cathodes are heated a discharge arc is struck between them thereby lighting the lamp and shorting out the switch.

It is desirable to mount the starting mechanism at a point where it is easily accessible for installation or replacement since in some cases it has been found that failure of the fluorescent lighting systems is due to failure of the starting switch. Failure of the reactor rarely, if ever, occurs inasmuch as the latter is constructed of relatively rugged material and seldom needs attention. If provision is made for easy replacement of the starting switch it is possible to take care of most cases wherein shutdown of the lamp is due to failure of the starting system.

To this end, a mounting socket 13 is provided to receive a starting switch mechanism 14, and these elements are constructed with coating 55

contact means so designed that the switch mechanism may easily be connected and disconnected from the mounting socket 13. Removal of the switch mechanism is accomplished simply by grasping it in the hand and turning it within the socket member. The socket 13 may be mounted at any convenient point, preferably adjacent the fluorescent lamp; by way of example it has been shown mounted on the reflector 10 surface 12. Referring to Fig. 4, the starting switch may be of the glow discharge type, for example, a switch such as that disclosed in the copending application of Wayne C. Smitley, Serial No. 289,897, filed August 12, 1939, and assigned to the same assignee as the instant application. The switch elements are contained within a sealed glass envelope 15 through which lead lines 16 and 17 conduct current to a pair of contacts 18 and 19. The contact 18 is formed 15 by a bent-over extension of the lead-in wire 16, while the contact 19 is a separate piece of wire mounted on a U-shaped bimetallic element 20 carried by the other lead-in wire 17. A piece 20 of emissive material 21 is placed on the bimetallic strip adjacent the bent-over extension of the lead-in wire 16 to increase the glow discharge between these two elements.

As shown in the circuit diagram of Fig. 5, the glow discharge switch is placed in series with 30 one of the terminals of the filament at each end of the fluorescent lamp. The other terminals of the filaments are placed in series with a reactor R and the lead lines of a power circuit. A switch S controls power to the assembly. Upon closure 35 of the switch S current flows through the reactor R and the left-hand filament of the lamp and thence to the lead-in wire 16, and a glow discharge takes place between this lead wire and the bimetallic strip secured to the lead wire 17 so 40 that current is conducted to the right-hand filament of the lamp and thence to the other side of the power line. The glow discharge between the lead wire 16 and the bimetallic strip at a point adjacent the emissive material 21 heats up 45 the bimetallic strip 20 and causes it to flex in a manner to close the contacts 18 and 19. Closure of these contacts applies full line voltage to the lamp filaments heating them to a point at which they give off an electron discharge. Closure of 50 the contacts likewise shorts out the glow discharge arc permitting the bimetallic strip to cool. However, due to the slight thermal lag in the bimetallic strip the contacts 18 and 19 remain closed for the order of $\frac{1}{2}$ to 2 seconds after cooling of the strip has been initiated during which

time the lamp filaments are being heated in the manner aforementioned. When these contacts open, the circuit through the lamp filaments is interrupted and the reactor produces an inductive surge across the filaments. This results in an arc discharge taking place between the filaments of the lamp so that the lamp lights. When this occurs current from the power line flows directly through the lamp arc discharge and shunts out the glow switch. In addition to providing an inductive surge for starting the lamp, the reactor limits the current through the filaments during the heating period and through the lamp during its operation. If desired, a small condenser C of approximately .006 mfd. may be placed across the lead-in wires 16 and 17 to prevent radio interference.

In order to provide a housing for the glow switch to facilitate easy connection with the support 18, the glass envelope 15 is enclosed within a cylindrical metal casing 24 having a liner of insulating material 25. The open end of the casing 24 is closed by means of an insulating fiber disk 26 provided with two spaced contact prongs 27 for electrical connection with the socket 13 in a manner to be described later. The condenser C is likewise enclosed within the casing 24 in a position immediately adjacent the glass envelope 27. In some cases it has been found that failure of the contacts 16 and 19 to close has resulted in prolonged heating of the glow switch under the action of the glow discharge between the lead-in wires 16 and 17. This may cause serious damage when the generated heat is confined within the casing 24. In order to prevent overheating of the switch mechanism and possible damage to the surrounding supporting structure, a fusible element 28 mounted on a supporting plate 29 of insulating material is likewise disposed within the casing 24. The fuse link 28 is responsive to the ambient temperature within the housing 24. Should the glow switch operate an undue length of time such as to cause possible burning or damage to the supporting structure, the fuse 28 will melt cutting off the supply of current to the glow switch. This is accomplished due to the fact that the fuse link is connected electrically in series with the starting glow switch, as shown in Fig. 5. In manufacture, the plate 29 is provided with a window 29' which frames the fuse link and provides space for the metal to separate upon melting of the link. The assembled plate and fuse link are dipped in a rosin lacquer. Upon melting of the link separation of the ends of the metal is facilitated by the capillary action of the lacquer layer, thereby effectively preventing arcing across the link.

Each of the contact prongs 27 is formed of a hollow pin or rivet 30, one end of which is peened over the disk 26 to secure it in position, and the other end of which is formed with an enlarged head 31 provided with a peripheral groove 32. In manufacture the condenser C is provided with lead wires 33 and 34 which are connected electrically in parallel with the switch mechanism and fusible element. To this end, the wires 16 and 33 are connected to one of the contact prongs 27. This is accomplished by inserting these wires within the hollow rivet 30 and fastening them in position by a drop of solder which flows down into the hollow rivet making a good electrical connection therewith. The lead-in wire 17 is then connected to one of the lead wires 35 of the fusible element, while

the other lead wire of this element and the lead 34 of the capacitance are connected to the other contact prong 27 by a solder joint in the manner just described. After the lead wires of the glow switch, capacitor and fusible element are connected to the contact prongs 27, the assembly is inserted within the housing 24 and the insulating disk 26 secured to the bottom of the housing by turning over lugs 36 extending from the edge of the container 24; the lugs rest in slots 37 in the disk 26.

The supporting socket 13 is formed with a housing 40 of insulating material, such as a phenolic condensation product and filler; the housing, in turn, is provided with an annular recess 41 for receiving the container 24. The bottom 42 of the recess is formed with two annularly arranged keyhole slots 43 for receiving the connector prongs 27. The enlarged ends 38 of the connector prongs extend through the keyhole slots and engage spring contact members 44 mounted on the bottom of the housing 40 and disposed at points adjacent the walls of the keyhole slots. Contact elements 44 are formed of spring wire which rest in the grooves 32 formed on the enlarged ends of the contact prongs. The container 24 is locked securely within the mounting socket simply by placing it in the recess 41, inserting the enlarged ends of the connector prongs 27 through the large openings in the keyhole slots and then slightly rotating the container to move the ends of the prongs beneath the narrower portions of the keyhole slots. In this position the switch prongs are in good electrical contact with the wire contact elements 44 since the latter are spring biased into engagement with the grooves 32. The spring contacts firmly engage the switch prongs and prevent the container 24 from being turned in the recess. This is accomplished by bending the wires 44 into the planes of the keyhole slots to form projections 45 which engage the rims of the prongs and hold them in seated portion, as shown in Fig. 3. The prongs are snapped past these projections upon rotation of the switch container.

The wire contacts 44 rest in shallow recesses 46 formed in the bottom of the housing 40 and are electrically connected to terminal plates 47 disposed at opposite ends of the housing in grooves 48; these electrical connections may be made by spot welding, soldering, or the like. Each of the terminal plates 47 is provided with a terminal screw 49 for receiving a connecting wire of the lamp circuit. In order to hold the terminal plates 47 and the contact wires 44 in position on the base, the recesses 46 and grooves 48 are closed by means of an insulating cover plate 50 formed of sheet fiber, or the like. The cover plate is held in position by drive screws 51. To facilitate mounting of the housing on any supporting surface, it is formed at opposite ends with openings 52 for the reception of any suitable fastening means.

The invention makes possible an arrangement wherein the starting switch of a fluorescent lighting system may be easily assembled in the system and may be readily replaced in case of failure without disturbing the associated lamp fixtures or reflectors of the system. Such would not be the case if the starting switch were permanently wired into the system. In addition, the container 24 provides a protective casing for the relatively fragile glow switch. Inasmuch as the glow switch is compact and the capacitor and fusible element are of small size, these members

may be assembled in a container of reduced size such that the switch may be installed in the small amount of space available in a lamp fixture. The capacitance C is utilized to reduce radio interference but, manifestly, in some cases, it may be omitted. Similarly, if desired, the fusible element may be omitted without affecting the operation of the glow switch.

What I claim as new and desire to secure by Letters Patent of the United States is:

1. In a starting mechanism for a discharge lamp, a housing having contact means adapted to engage the contacts of a receptacle, a switch mechanism confined within said housing including thermally responsive contact members operated by the heat of a glow discharge there-between to control the flow of current to the lamp, a circuit interrupting means likewise confined within said housing and being electrically connected in series with said switch mechanism, said means being operable in response to increase in the ambient temperature within said housing upon continued unwarranted operation of said glow discharge to interrupt the flow of current through the switch.

2. In a starting means for a discharge lamp, a housing provided with contact means adapted to engage the contacts of a receptacle, an en-

velope having a switch mechanism therein located within said housing, said switch mechanism including thermally responsive contact means and means for creating a glow discharge 5 to heat said contact means, and a fusible element disposed within said housing adjacent said envelope and being electrically connected in series with said switch mechanism, said element being fusible upon continued unwarranted operation 10 of said glow discharge means to interrupt the flow of current through the switch.

3. In a starting mechanism for a discharge lamp, a housing having contact means adapted to engage the contacts of a receptacle, a switch 15 mechanism confined within said housing including thermally responsive contact members operated by the flow of current in a starting circuit to control the flow of current to the lamp, a circuit interrupting means likewise confined within 20 said housing and being electrically connected in series with said switch mechanism, said means being operable in response to increase in temperature within said housing upon continued unwarranted flow of current in the starting circuit 25 to interrupt the flow of current through the switch.
